UNITED STATES PATENT OFFICE.

OSCAR ALEXANDER AND MAX ALEXANDER, OF NEW YORK, N. Y.

BED-LOUNGE.

SPECIFICATION forming part of Letters Patent No. 325,897, dated September 8, 1885.

Application filed July 14, 1884. (No model.)

To all whom it may concern:

Be it known that we, OSCAR ALEXANDER and MAX ALEXANDER, citizens of the United States, residing at New York, in the county 5 of New York and State of New York, have invented certain new and useful Improvements in Bed-Lounges, of which the following is a specification, reference being had therein to the accompanying drawings.

10 My invention relates to certain improvements in bed-lounges, and is designed objectively to produce a piece of furniture that shall serve the purpose of a lounge or sofa, and when opened a bed, the necessary mattresses 15 and springs being within the body.

The improvement consists, essentially, in the economical arrangement for the disposition of the legs when the device is used as a lounge and in the manner of supporting the 20 head.

In describing the device reference will be had to the accompanying drawings, in which Figure 1 represents a perspective of the device as a lounge; Fig. 2, a detail of one of the 25 legs, and Fig. 3 a perspective of the device as a bed.

A designates the body of the device, having formed on it a back, B. These parts may be ornamented as is desired, and the back cushioned.

30 Normally resting on the body is a cushioned top, C, hinged thereto so as to open, as shown in Fig. 3, the surfaces D being then coincident or level, and are mattressed over springs or arranged in any other suitable manner to 35 provide for the comfort of the occupant.

The hinged piece C is provided at the head with a leg, E, and at the foot with a leg, F. The leg E is formed of angular stuff and is 40 bent so as to conform to and rest in the space formed by the conjunction of the back and the head-piece. Thus the leg is solidly and strongly fixed to the hinged piece and is folded completely out of the way when it is desired 45 to use the device as a lounge; also, preventing dirt from entering the space, always occurring at the junction of the head-piece and the back.

One side of the angular leg is continued above the surface of the piece C, as shown at 5 G, and on it engages a catch, H, on the hinged head-piece I. Thus the strain is communicated directly to the leg, and that part of the device is best adapted to receive it.

The rear leg is also strongly and rigidly 5 fixed to the piece C, and is provided with an indent or concave portion, K, which, when the device is "closed," fits over the "bulge" of the cushion on the back, the free end of the leg closely hugging the said back above the 6 cushion.

Thus it is evident that while the weakness and also the machinery attending folding legs is obviated the rigid legs are no more in the way, while the front leg has the additional 6: desirable features of directly supporting the head and also preventing the entrance of dirt in the space in which it rests when the device is closed.

Since stops or catches on the extensible portions of both the body and head, by means of which the head is supported, are not new, they are, in the broad sense, here disclaimed.

Having described the device, what I claim is—

1. In a bed-lounge, a hinged extending piece provided with an angular curved leg on which is formed an extension or flange, in combination with a head having on it a catch engaging with the extension on the leg.

2. A bed-lounge having a hinged extension provided at the foot with a leg having an indent or concave recess, and at the head an angular curved leg with an extension at its base, and a head having a catch which engages with 85 the extension on the leg, the hinged extension folding on the body of the device to form the lounge and out from it to form the bed.

In testimony whereof we affix our signatures in presence of two witnesses.

OSCAR ALEXANDER.
MAX ALEXANDER.
